(57) **CLAIM**

The ornamental design for a cat exercise wheel, as shown and described.

DESCRIPTION

FIG. 1 is a left front perspective view of a cat exercise wheel, showing our new design;

FIG. 2 is an elevational view of the right side thereof, the elevational view of the left side being a mirror image thereof;

FIG. 3 is a top plan view, thereof;

FIG. 4 is a front elevational view, thereof;

FIG. 5 is a rear elevational view, thereof; and,

FIG. 6 is a bottom plan view, thereof.
